UNITED STATES PATENT OFFICE.

THEODORE W. FOSTER, OF PROVIDENCE, RHODE ISLAND, ASSIGNOR TO THEODORE W. FOSTER AND BROTHER COMPANY, A CORPORATION OF MAINE.

DESIGN FOR A VANITY CASE.

Application filed November 25, 1921. Serial No. 517,795. Term of patent 3½ years.

To all whom it may concern:

Be it known that I, THEODORE W. FOSTER, a citizen of the United States, residing at Providence, in the county of Providence and State of Rhode Island, have invented a certain new, original, and ornamental Design for a Vanity Case, of which the following is a specification.

In the accompanying drawings which form a part of this specification,

Figures 1 and 2 are a front elevation and a side elevation respectively of a vanity case embodying my new design.

An essential feature of this design is the peripheral contour of the body portion thereof.

I claim:

The ornamental design for a vanity case, as shown.

THEODORE W. FOSTER.
